UNITED STATES PATENT OFFICE.

EDWARD J. PRECOURT, OF PORTLAND, MAINE.

VENTILATING-COWL.

SPECIFICATION forming part of Letters Patent No. 781,739, dated February 7, 1905.

Application filed May 13, 1904. Serial No. 207,886.

To all whom it may concern:

Be it known that I, EDWARD J. PRECOURT, a citizen of the United States of America, and a resident of Portland, Cumberland county, 5 State of Maine, have invented certain new and useful Improvements in Ventilating-Cowls, of which the following is a specification.

My invention relates to a chimney-cowl; and the object of the invention is to construct 10 such a cowl in which no downdrafts can be created by the movement of the external air and in which such air movements will create the greatest possible vacuum, and thus help the draft of the chimney.

15 The invention consists of the combination and arrangement of parts hereinafter described and claimed.

I illustrate my invention by means of the accompanying drawings, in which—

20 Figure 1 is a vertical central section through my cowl, and Fig. 2 is a section on the line X X of Fig. 1.

The body of the cowl is made up of an outer tube, the lower portion *a* of which is cylindrical in form and adapted to be inserted into 25 the top of the chimney-flue. The upper end *b* is formed into an inverted cone having on the upper edge thereof a deflecting-flange *c*, which inclines outwardly and downwardly, extending both inside and outside of the edge of 30 the cone. Within the conical portion of the outer tube is the inner tube *d* of smaller diameter than the outer tube, so that there is formed between them an annular downward-tapering space. The upper end of the inner tube is preferably slightly above the upper 35 edge of the cone *b*, so that the upward-deflected air from the flange *c* will pass upward over the end of the inner tube. Just below 40 the upper end of the inner tube is a deflecting-flange *e*, extending outward and downward substantially parallel with the flange *c*.

The upper end of the cowl is formed of a 45 conical hood *f*, located above the upper end of the cone *b*, so as to allow a space for the escape of the smoke and gases.

For the purpose of handling and adjusting the parts I connect the hood and the inner

tube with the ring *g*, which fits the cylindrical portion of the outer tube. Braces *h* are secured at their lower ends to the ring and thence extend to the inner tube, when they are riveted or otherwise fastened, and they terminate in the under side of the cone *f*, to which they are secured. Thus when the cone *f* is lifted out the inner tube and the ring come with it, and the ring supports the members in place with the lateral bearing, which the braces have on the inner edge of the flange *c*.

It will be seen that a cowl thus constructed will deflect the external air upward from the flange *c*, from whence it will pass over the top of the inner tube, creating a vacuum there and in the annular space around the inner tube. By the operation of the flange *e* downward currents are prevented from passing through the annular space.

I claim—

1. The herein-described chimney-cowl consisting of an outer tube having its upper end formed into an inverted cone, an outwardly and downwardly inclined flange on the upper edge of said cone, an inner tube within said cone and separated therefrom, an outwardly and downwardly inclined flange around the upper end of said inner tube substantially at the same level as the top of said cone, and a conical head above the upper end of said cone.

2. The herein-described chimney-cowl consisting of an outer tube having its upper end formed into an inverted cone, an outwardly and downwardly inclined flange on the upper edge of said cone, an inner tube within said cone and separated therefrom, an outwardly and downwardly inclined flange around the upper end of said inner tube substantially at the same level as the top of said cone, a conical hood above the upper end of said cone, a ring fitting the outer tube below said cone and supporting-braces connecting the ring, the inner tube and the conical hood.

EDWARD J. PRECOURT.
